UNITED STATES PATENT OFFICE.

SAMUEL KELLETT, OF SAN FRANCISCO, CALIFORNIA.

DESIGN FOR CENTER-PIECE.

Specification forming part of Design No. **8,016**, dated January 19, 1875; application filed January 2, 1875.
[Term of Patent 14 years.]

No. 4.

To all whom it may concern:

Be it known that I, SAMUEL KELLETT, of the city and county of San Francisco, California, have invented and produced a new and original Design for a Center-Piece, reference being had to the accompanying photograph and to letters marked thereon.

My new design consists of a drop, A, lyre-shaped form, composed of bands and scrolls B and C finished right and left on a plain ground. Shell D in center of figure, with stem and leaf extending to the outer edge of panel. This described figure is repeated, forming four

panels, around which moldings are formed, curling on connection, from which a stem of flowers, leaves, and buds extend to outer edge of center-piece.

Having thus described my invention, what I claim, and desire to secure by Letters Patent, is—

This new and original form of center-piece, as shown in photograph.

SAML. KELLETT.
